UNITED STATES PATENT OFFICE.

FRANCIS BILLINGHAM, OF BROOKLYN, NEW YORK.

DESIGN FOR A LAMP OR LANTERN BODY.

SPECIFICATION forming part of Design No. 18,201, dated March 27, 1888.

Application filed February 3, 1888. Serial No. 262,939. Term of patent 14 years.

To all whom it may concern:

Be it known that I, FRANCIS BILLINGHAM, a citizen of the United States, residing in the city of Brooklyn, Kings county, and State of New York, have invented and produced a new and original Design for the Body of a Lamp or Lantern, of which the following is a specification, reference being had to the accompanying drawing, forming part thereof, one figure in perspective being deemed sufficient to illustrate my design.

The leading feature of my invention relates more especially to the surface configuration of the faces of the lamp-body; and it consists in the ornamental figures subdividing each face with an oval or elliptic band, B.

The figures composing my design are: A, a central figure of elliptical form surrounded by a narrow band, B, of uniform width, which is also elliptical in outer outline, tangential to which and adjoining its ends and sides is the inner outline of a right-angled band, C, or oblong square, the outer outline of which is the outline of the lamp-face and the outer contour of my design. Four right-angled triangular figures, D E F G, occupy the spaces between the outer outline of the elliptical band

B and the inner outline of the oblong square band C. The surfaces of these figures and the central elliptical figure are slightly elevated from the common plane and slope or bend at the edges, as shown by the lines *a a a a*.

I claim—

The design for a lamp-body, consisting of an outer contour or shape of the lamp-body such as shown, with the ornamental surface configuration of the faces, with a central figure of elliptical form surrounded by a narrow band of uniform width, also elliptical in outer outline, the ends and sides of which are tangentially joined by the inner outline of a right-angled band, the outer outline of which forms the outer outline of the lamp-face, and four right-angled triangular figures occupying the spaces between the outer outline of the elliptical band and the inner outline of the right-angled band, in the manner shown and described.

In testimony whereof I have signed my name, in presence of two witnesses, this 27th day of January, 1888.

FRANCIS BILLINGHAM.
